UNITED STATES PATENT OFFICE.

WILLIAM L. DE REMER, OF CHICAGO, ILLINOIS, ASSIGNOR TO REPUBLIC RAILWAY APPLIANCE COMPANY, OF ST. LOUIS, MISSOURI, A CORPORATION.

DRAFT-RIGGING.

No. 868,915.

Specification of Letters Patent.

Patented Oct. 22, 1907.

Application filed October 22, 1906. Serial No. 339,953.

To all whom it may concern:

Be it known that I, WILLIAM L. DE REMER, a citizen of the United States of America, residing in Chicago, in the county of Cook and State of Illinois, have invented certain new and useful Improvements in Draft-Riggings, of which the following is a full, clear, and exact description, reference being had to the accompanying drawings, forming part of this specification.

My invention relates to that class of draft riggings for railway cars wherein there is employed one or more coil springs arranged longitudinally in line with the draw bar and one or more coil springs arranged transversely of the length of the draw bar and combined with V-shaped longitudinal friction blocks that coöperate with other V-shaped transverse friction blocks that are connected to or carried by the draw bar, the construction being such that the first part of the movement of the draw bar in either direction is resisted by the first mentioned longitudinally arranged spring or springs and after these springs have been compressed the further movement of the draw bar is resisted by the transversely arranged springs and the friction blocks referred to.

The object of my invention is to simplify a construction of this character of draft rigging and to increase its durability, and also facilitate the repair and replacement of worn and broken parts.

My invention consists in features of novelty herein-after described and claimed.

Figure I is a bottom view of my improved draft rigging, part in horizontal section and with one of the supporting plates removed. Fig. II is a side view, part in vertical section. Fig. III is a transverse vertical section taken on line III—III, Fig. I. Fig. IV is an inside view of one of the retaining nuts or caps of the transversely arranged springs. Fig. V is an outside view of one of the nuts or caps. Fig. VI is a perspective view of the inner or rear friction block.

Referring to the drawings: 1 represents the draft timbers or sills of a car body to the inner or adjacent faces of which supporting slides are permanently secured. These slides consist of vertical side plates 2 having integral inturned upper flanges 3 and detachable lower flanges 4 suspended from the upper flanges 3. The side plates are secured to the draft timbers or sills by means of bolts 5 and the lower flanges 4 are secured to the plates 2 by means of bolts 6 that pass up inside of the plates and extend through the upper flanges 3 as shown clearly in Fig. II.

7 represents the inner end of the draw bar to which is secured a strap 8 by means of bolts 9. This strap is of U-shape and extends back to or nearly to the inner ends of the slides already referred to.

10 represents an outer follower-plate against which 55 the inner end of the draw bar bears, and which rests

upon the removable flanges 4 of the slides and is adapted to move back and forth thereon.

11 represents a longitudinal front friction block which also acts as an inner follower-plate. This friction block also rests upon the removable flanges 4 of the slides and between it and the outer follower-plate 10 is a longitudinal coil spring 12 which may inclose another longitudinal coil spring 13. The outer follower-plate 10 has a guide stem 14 and the front friction block 11 has a like stem 15 but of greater length. The longitudinal springs 12 and 13 surround these stems and are held thereby from dropping out of position.

The inner face of the front friction block 11 is V-shaped as shown in Fig. I and bears against correspondingly V-shaped faces of transverse friction blocks 16 and 17 situated just back of the front friction block 11. The transverse friction blocks 16 and 17 are supported by a bolt 18 passing freely therethrough and the outer ends of which are provided with nuts or caps 19 that rest upon the lower flanges 4 of the slides, the nuts or caps being four-sided as shown in Figs. IV and V and of sufficient size to substantially fill the spaces between the upper and lower flanges of the slides, as shown in Fig. III. The transverse friction blocks 16 and 17 have central hubs 20 between which and the respective nuts or caps 19 are located transverse coil springs 21 that extend in a direction transverse to that of the length of the draw bar.

Back of the transverse friction blocks 16 and 17 there is located a longitudinal rear friction block 22 that also rests on the lower flanges of the slides and the forward face of which is formed V-shaped to fit the corresponding faces of the inner ends of the transverse friction blocks 16 and 17. The rear end of the rear friction block 22 is provided with inwardly extending lugs or ears 23 between which fits the inner end of the strap 8. The rear friction block 22 is provided with a series of strengthening ribs 24 embraced by the strap and the inner faces of the transverse friction blocks 16 and 17 are formed with series of channels or grooves for decreasing the weight of the transverse friction blocks and thus provide series of strengthening ribs 25. The inner faces of the longitudinal friction blocks 11 and 22 are formed with stop lugs 26 adapted to come against flat faces or shoulders 27 on the respective sides of the outer faces of the transverse friction blocks 16 and 17 for the purpose of limiting the outward movement of the transverse friction blocks 16 and 17.

In operation the inward and outward movement of the draw bar is first resisted by the longitudinal springs 12 and 13. If these springs are insufficient to counteract the entire force exerted on the draw bar then the longitudinal friction blocks 11 and 22 begin to move with relation to the transverse friction blocks 16 and 17 whereupon the transverse springs 21 commence to 110

act to resist the movement of the draw bar, the front friction block 11 co-acting with the transverse friction blocks 16 and 17 to resist inward movement of the draw bar and the rear friction block 22 co-acting with 5. the transverse friction blocks 16 and 17 to resist excessive movement of the draw bar in an outwardly direction.

The parts are few in number, thus reducing the first cost of production and reducing to a minimum the 10 cost of maintenance, and also combining the greatest possible strength with the least number and weight of parts. Inasmuch as the rigging is supported directly upon the removable lower flanges of the slides the matter of repair is made simple and easy, for all that 15 it is necessary to do in case repairs are required is to remove the lower flanges of the slides when the rigging can be lowered from its working position and taken out from beneath the car to be worked upon and repaired, and when repaired can be very quickly and conveniently replaced. The slides are provided with outer 20

end ears 30 to limit the outward movement of the following lower-plate 10 and with inner end ears 31 to limit the inward movement of the rear friction block 22.

I claim:

1. A draft rigging comprising ~~V-shaped front and rear~~ 25 friction blocks having stop lugs upon their inner faces, and V-shaped transverse friction blocks having flat shoulders upon their sides; the front and rear friction blocks being adapted to slide upon the transverse friction blocks until the stop lugs come in contact with the flat shoulders 30 to arrest the movement of the blocks.
2. A V-shaped rear friction block for draft rigging provided at its rear end with inwardly extending lugs and a series of strengthening ribs between the inwardly extending lugs. 35
3. A V-shaped transverse friction block for draft rigging formed with a series of channels or grooves providing a series of strengthening ribs upon its inner face.

WILLIAM L. DE REMER.

In presence of—

BLANCHE HOGAN,
NELLIE V. ALEXANDER.
